UNITED STATES PATENT OFFICE

GEORGE D. OVERHOLTZ, OF FAIR OAKS, PENNSYLVANIA, ASSIGNOR TO MCCLINTIC-MARSHALL COMPANY, OF PITTSBURGH, PENNSYLVANIA, A CORPORATION OF PENNSYLVANIA

OUTDOOR ADVERTISING STRUCTURE

Application filed June 16, 1930. Serial No. 461,269.

This invention relates to outdoor advertising structures, and particularly to new and improved border elements, as cornices, sills, columns, column capitals, column bases, and sub-bases, and means for mounting and supporting said elements.

In the drawings, I have shown a bulletin construction, but my invention is not to be limited thereto, as it may be advantageously embodied in poster panel constructions of outdoor advertising structures.

In outdoor advertising structures, whether of the bulletin type or the poster panel type, it is highly desirable that the structure should be of such character that it may be readily set up and taken down; also, that the panels, particularly in the bulletin type, may be removed from and applied to the structure with a minimum of trouble and expense. The present invention embodies a construction having the said qualities, and, in addition thereto, comprises novel border elements and simple and efficient mountings for said elements.

25 In the accompanying drawings, which illustrate an application of my invention:

Fig. 1 is a front elevational view of an outdoor advertising bulletin constructed in accordance with my invention;

30 Fig. 2, is a broken perspective view, particularly showing the interior of a corner of the structure;

Figs. 3, 4, 5 and 6, horizontal sections taken on lines III—III, IV—IV, V—V and VI—

35 VI, respectively, of Fig. 2; and

Fig. 7, a horizontal section taken on line VII—VII of Fig. 1.

Referring to the drawings, 5 designates uprights of a steel framing employed for supporting the elements entering into the bulletin construction, and 6 are horizontally extending members of the framing. The removable panels 7 are detachably secured to the framing by means of L-bolts 8.

40 The border elements of frame of the structure are all preferably made from sheet metal, bent and shaped to provide an attractive appearance when assembled in the bulletin structure, and, as illustrated, include a top cornice member 9, a bottom sill member 10,

and column members proper 11. Each of the columns 11 includes a column capital 12 and a column base 13. Corner sub-bases 14 and intermediate sub-bases 15, also made of metal, are associated with the border elements. In 55 addition to the parts mentioned, the structure includes a lattice 16, in this instance made of wood, although a metallic lattice may be employed.

As illustrated and as preferred, the cornice member is reinforced by two angle bars 17, and is mounted on a plurality of brackets 18, the latter being attached to the uprights 5.

The column structures are arranged at opposite ends of the bulletin and in spaced relation to the framing proper, but in overlapping relationship with the panels of the structure and portions of the said framing. The means for mounting the parts or elements entering into the columns, constitute 60 important and characteristic features of the present invention. These columns, when assembled with the framing, panels, etc., constitute the vertically extending side or end corners of the structures, and, in effect, each 65 forms a continuous corner structure of attractive design and one that may be mounted upon a corner sub-base member, as particularly shown by Fig. 1.

The mountings for said columns include 70 supplemental vertically extending angle members or uprights 19 secured to the outer ends of the horizontal members 6, in vertical planes lying beyond the side edges of the panels and spaced away from the outermost 75 uprights 5 of the framing by means of bolts 20. Uprights 19 extend throughout the height of the structure, and are designed to carry a plurality of brackets, the latter being 80 adapted to be entered in and secured to the respective elements entering into the construction of the columns, as well as the corner sub-bases.

Thus, I employ brackets 21 for the column capitals, brackets 22, brackets 23 for column bases 13, and brackets 24 for the sub-bases 14. The bracket members 22 are each slotted, as at α , through which bolts 25 are passed to secure the said brackets to the supplemental 95 uprights. The provision of slots α allows for 100

the desired amount of adjustability when assembling the parts.

For example, when it is desired to employ panels 7 of other than the standard thickness, 5 the brackets 22, 23 and 24 may be so adjusted on the supplemental uprights 19 by means of the slotted openings *a*, as to provide for the adaption of the border construction, and more specifically the columns and their parts, 10 to various types of panels.

All of said brackets are provided with right angle flanges *b*, having a plurality of openings therein for the purpose of securing the sheet metal column structures thereto by 15 means of suitable screws or bolts. Such an assembly of parts within the column structures provides for rigidity by reason of the supplemental uprights 19 and their associated brackets, the latter in turn being secured to 20 the sheet metal structures as prescribed.

In addition to the brackets 24, within the corner sub-bases 14, I have provided additional brackets or reinforcing members 24*a* positioned within the front portions of said 25 sub-bases, secured to the sheet metal thereof and bolted the flanges of the brackets 24, as at *c*. Thus, in addition to the transverse reinforcement produced by the brackets 24, longitudinal strength is given to said sub-bases 30 by means of the brackets 24*a*.

I claim:

1. In an outdoor advertising structure, the combination with a supporting steel framing including metallic upright and horizontally 35 extending members, panels on the framing, a supplemental metallic upright spaced beyond the panels and attached to a horizontal member of the framing, a hollow metallic column member spaced from the panels and positioned over the supplemental member, and metallic angular brackets within the 40 column and attached to the supplemental member and column member.

2. In an outdoor advertising structure, the combination with a steel supporting framing 45 including metallic upright and horizontally extending members, panels on the framing, a metallic supplemental upright spaced beyond the panels, a hollow metallic column member spaced from the panels and positioned over the supplemental member, and adjustable metallic brackets attached to the supplemental member and column member 50 arranged in different planes and within the column.

3. In an outdoor advertising structure, the combination with a steel supporting framing including upright and horizontally extending members, panels on the framing, a supplemental upright spaced beyond the panels, a hollow metallic column member spaced from the panels and positioned over the supplemental member, including a hollow capital 60 element and a hollow base element positioned 65 at opposite ends of the column, a bracket en-

tered in the column for attaching it to the supplemental member, a bracket entered in the capital element for attaching it to the supplemental member, and a bracket entered in the base element for attaching the latter 70 to said supplemental member.

In testimony whereof I affix my signature.

GEORGE D. OVERHOLTZ.
